Primary Examiner — Jack Reickel*Assistant Examiner* — Salamah Jordan(74) *Attorney, Agent, or Firm* — Marks & Clerk; Wilfred So(57) **CLAIM**

The ornamental design for a kettlebell, as shown and described.

DESCRIPTION

FIG. 1 is a top perspective view of a kettlebell showing our new design, according to a second embodiment;

FIG. 2 is a bottom perspective view thereof;

FIG. 3 is a front view thereof, with a rear view thereof being identical;

FIG. 4 is a right side view thereof, with a left side view thereof being identical or a mirror image;

FIG. 5 is a top view thereof; and,

FIG. 6 is a bottom view thereof.

In FIGS. 1-6 of the kettlebell, the broken lines depicting the weight plates, the bar going through the weight plates, and the stoppers on the bar form no part of the claimed design.
